UNITED STATES PATENT OFFICE.

PATRICK MCCULPHA, OF NEW YORK, N. Y.

HOT-AIR FURNACE.

SPECIFICATION forming part of Letters Patent No. 359,734, dated March 22, 1887.

Application filed September 24, 1886. Serial No. 214,456. (No model.)

To all whom it may concern:

Be it known that I, PATRICK MCCULPHA, of the city, county, and State of New York, have invented a new and useful Improvement in 5 Hot-Air Furnaces; and I do hereby declare that the following is a full and exact description thereof, reference being had to the accompanying drawings, and to the letters of reference marked thereon, making a part of this 10 specification, in which—

Figure 1 is a front elevation of my improved hot-air furnace; Fig. 2, a plan of same with the top removed, and Fig. 3 a vertical longitudinal section in line $\alpha\alpha$ of Fig. 2.

15 Similar letters of reference indicate like parts in each of the figures.

My invention relates to that class of furnaces which are constructed with hot-air tubes, each of which passes independently through the 20 combustion-chamber, and from thence directly to the apartment to be heated.

It has for its object to simplify the construction of the furnace and increase its efficiency for delivering large volumes of pure, fresh, 25 warm air into the building and equally under all conditions to each of the rooms to be heated and ventilated.

It consists in the combination of a U-shaped air-supply chamber formed of pipes extending 30 in a rectangle around three sides of the upper part of the combustion-chamber of the furnace, and whose two ends both open directly into the outer air, with a series of small delivery-pipes fitted into the transverse arm of 35 the supply-chamber, to extend thence independently horizontally or with a slight upward inclination entirely across the furnace, each to connect with a separate conducting-tube leading to one of the apartments in the 40 building.

I prefer to construct the outer walls, A A A', of my furnace of brick in a rectangular form, either square or oblong, the pipes in the latter case being fitted to extend lengthwise thereof.

45 At the front end of the furnace I form a fire pot or chamber, B, fitted with a grate, C, of any approved construction over a suitable ash-pit, D. This fire-pot is lined with fire-brick in the customary manner. It is made 50 much smaller than the body of the furnace and

the space at the sides and rear thereof are preferably filled in, to retain the heat imparted thereto, insure a more uniform and constant temperature, and facilitate the maintenance of the fire after the furnace has been put into 55 operation.

In the upper part of the chamber E, which is inclosed by the outer walls, A A A', of the furnace, three large wrought-iron gas-pipes, F F F', are fitted and united by means of the 60 elbows G G, to form a U-shaped or rectangular air-supply chamber, and are supported within the upper portion of the chamber E near to the walls thereof, as shown in Fig. 2. The two lateral pipes F' F' of this U-shaped 65 chamber are made to extend out through the rear wall, A', of the furnace with a close joint, and are preferably both continued through the outer wall, W, of the building, so as to open directly into the fresh outer air. 70

The front transverse section or pipe, F, of the supply-chamber is mounted directly over the fire pot or chamber B. To this front section, F, the delivery-pipes H H H are connected. These delivery-pipes are preferably 75 formed of wrought-iron tubes, which are screwed directly into holes tapped in the side of the section F, and which, extending thence across the furnace from front to rear in lines parallel with each other and with the side 80 pipes, F' F', project, each with a tight joint, through its rear wall, A', and are fitted with elbows to receive each a separate conducting-tube, R, leading to some one of the several apartments to be heated. 85

By observing a due proportion between the size of the pipes F F' F', forming the U-shaped air-supply chamber, and of the separate delivery-pipes H H H, extending thence out from the furnace, with reference to each other and 90 to the size of the fire-pot and furnace, as many pipes may be used as there are rooms to be heated, so that each shall receive a constant and independent supply of pure hot air.

The rear wall of the fire-pot B is carried up 95 entirely across the furnace-chamber nearly to the under side of the delivery-pipes H H, so as to form a bridge-wall, which will carry the flames and products of combustion directly up against the pipes. The chimney or discharge- 100

flue K for the furnace is located centrally at its rear end, so as to cause the hot gases to sweep along, over, and between the tubes H H.

The top of the furnace may be arched over 5 or be closed, as shown in the drawings, by an iron plate, S, upon which an outer lining of brick, T, is placed.

In the operation of the furnace the outer air entering the two lateral pipes F' F' flows in 10 through these pipes toward their central connecting-pipe, F, and the air in passing through these lateral pipes is measurably heated before it reaches the central pipe. In this central pipe, F, it is subjected more directly to 15 the heat of the fire, and expanding therein creates an outward pressure in the delivery-pipes H H, which open into it, and thus a strong current is formed in each of said pipes, the inward flow in opposite directions from the two 20 lateral pipes F' F' at each end of the connecting-pipe F serving to insure a constant, uniform, and equable supply to each delivery-pipe. The delivery-pipes H H are subjected to the 25 full heat of the fire throughout their length, and the heated air flowing through them from the front pipe, F, becomes rapidly hotter and passes out through the conducting-tubes R R into each apartment at a suitable temperature 30 to heat the same, and in such volume and under such conditions as respects freshness and purity as to insure the healthfulness thereof. The rapidity of the flow of the air prevents it from losing its vitality by deoxygenation in contact with the hot pipes and prevents the 35 latter from overheating, while the simple arrangement of the air-conducting pipes coupled by threaded joints prevents the possibility of any leakage of gas thereinto from the combustion-chamber.

40 The furnace is constructed at a comparatively low cost, and its economy of fuel and efficiency, as proven by practical tests, render it superior to the cast-iron furnaces in general use.

45 I am aware that a hot air furnace has heretofore been constructed with one or more independent hot-air pipes extending directly through the furnace, opening outwardly on one side to receive the air and connected at 50 the other, each to a conducting-tube leading to an apartment to be heated; but where the hot-air pipes are thus led directly through the furnace, each having an independent external connection with a cold-air supply, the passage 55 of the cold air is too rapid to insure proper heating, and the furnace is not effective or economical. By my invention I insure the requisite freedom of flow and constancy and adequacy of supply needed to afford good ventilation, and at the same time obtain, with 60 economy of fuel, a proper elevation of temperature by the combination of the large U-shaped air-chamber consisting of air-supply pipes in

the form of a rectangle placed within the furnace, but opening freely at both ends into the outer air, with a series of independent delivery-pipes, each connected within the furnace to the transverse arm of the U-shaped open-ended chamber, and arranged to extend thence across the hottest part of the furnace before 65 passing out to the several apartments which they are designed to supply.

I am also aware that grates have been constructed with hollow grate-bars opening into the apartment to be heated and connected 70 with upright flues at the rear, extending forward above the grate to open also into the same apartment, whereby a circulation of air is produced from the apartment through the grate-bars and flues back into it again, provision being made for an admission of fresh air, if desired, into said flues; but this system differs from my invention in that the lower flues or hollow grate-bars are covered by the ashes and cinders under the incandescent fuel 75 in the grate, and that the upper flues are exposed to the drafts or cold air entering the grate over the fire, so that said system of flues, while useful as an auxiliary to an open grate in heating a single apartment in which it is 80 placed and in producing a circulation of warm air in the apartment, is wholly unsuited and inoperative for the purposes of a furnace in heating a number of separate apartments, and my invention differs from these grates, not 85 only in the arrangement and combination of the heating-tubes with the furnace, as herein-before described, but also in the results attained by said arrangement and combination.

I claim as my invention—

The combination, with the fire-pot and heating-chamber, in a furnace, of a rectangular or U-shaped air-supply chamber, mounted in the upper portion of the heating-chamber, with its transverse arm or bend over the fire-pot 105 and its lateral arms extending horizontally along the sides of the chamber, both opening freely outwardly to receive a fresh-air supply, a series of parallel delivery-tubes connected to said transverse arm to open freely thereinto, and extending thence each independently through the upper portion of the heating-chamber from front to rear between said lateral arms, and separate conducting-flues, each 110 communicating with one of said delivery-tubes, and extending thence to one of the several 115 apartments to be heated, all substantially in the manner and for the purpose herein set forth.

In testimony whereof I have signed my name 120 to this specification in the presence of two subscribing witnesses.

PATRICK McCULPHA.
